STARTING AND OPERATING CIRCUITS FOR FLUORESCENT LAMPS

William S. H. Hamilton, Larchmont, N. Y.

Application November 4, 1952, Serial No. 318,609

6 Claims. (Cl. 315—100)

This application is a continuation in part of my prior application Serial No. 230,185, filed June 6, 1951, now Patent No. 2,717,332.

This invention relates to starting and operating circuits for fluorescent lamps, and particularly for A. C. and D. C. fluorescent lamps which are more or less difficult to start and require an inductive kick to start them.

More particularly, the present invention relates to circuit organizations embodying a combined thermal and magnetic type starter having normally closed thermal and magnetic starting contacts and a magnetic coil, the combination being so arranged that when the thermal starting contacts open, the coil is energized by the pre-heating current through the lamp filament or filaments to cause the magnetic contacts to be opened very rapidly to start the lamp, the coil thereafter remaining in series with the lamp while the lamp is operating, holding the magnetic starting contacts open by magnetic means and the thermal starting contacts open by means of an insulated mechanical interlock connected to said magnetic contacts, thus allowing cooling of the heater for the thermal starting contacts without permitting the thermal starting contacts to reclose, the circuits including reactance means for giving an inductive kick when the magnetic starting contacts open, whereby the lamp, if in normal condition, will fire and the lamp will operate until the line voltage is interrupted when the coil will be de-energized and both starting contacts will immediately reclose, enabling the lamp to restart without delay upon another application of line current.

The primary object of the invention is to provide in a starter embodying these features current actuated means for automatically cutting out or locking out the starter in the attempted starting of a defective lamp or one which has passed its useful life period, in order to prevent injury to the starter or other components of the circuit.

Another object of the invention is to provide a starter which may be reversible in its socket.

A further object is to provide a starter which will prevent the annoying "ghost lighting," objectionable in the use of certain types of long lamps when cut out of action by conventional starters now used.

The invention will be understood from a consideration of the accompanying drawings and the following detailed description.

In these drawings:

Fig. 1 is a diagrammatic view of a circuit for D. C. lamps employing a reactor and a starter embodying my invention, said starter including a quick restarter as well as a cut-out or lock-out means of the character referred to.

Fig. 2 is a diagrammatic view of a circuit similar to that of Fig. 1 but adapted for A. C. or D. C. use.

Figs. 3, 4 and 5 are schematic obverse, reverse and side elevational views of a starter embodying the quick restarter and the cut-out or lock-out means, showing only the basic features of the starter and omitting the wiring connections.

2

Figs. 6, 7 and 8 are diagrammatic views showing further modified circuit arrangements for D. C., A. C., or D. C. and A. C. use, respectively, and each embodying quick restarting and cut-out or lock-out means of the character described, which lock-out means when operated disconnects one line terminal from the lamp to prevent "ghost lighting."

In the schematic showing of the starter in Figs. 3, 4 and 5, A' designates an insulated base carrying contact pins 1, 2, 3, 4, and an insulated upright A'', which in practice are enclosed in a housing or casing, not shown. On this upright are mounted a relay coil C, a spring retracted relay armature switch S1, two thermally responsive or thermostatic switches S2, S3 and heaters H1, H2 and H3, for the switches, which are connected in the manner shown in those circuits employing the switch S3 and its heaters, H2 and H3 for a lock-out action, which switch and its heaters may be omitted from a starter designed for general use but used most commonly in circuits not employing a lock-out action, the inclusion or omission of such switch and its heaters involving merely changes in the wiring arrangements.

The switches, which are of self-closing type and normally closed are not physically coupled for conjoint action, but are independently movable, switch S1 under action of the coil C and switches S2, S3, in response to their heaters, with the exception that a quick restarter in the form of a mechanical interlocking connection (controlled by the armature actuated by the coil and generally designated MIC in the drawings) is interposed between switches S1 and S2, and is provided for holding switch S2 open together with switch S1 under the electro-magnetic attraction of the coil C when the latter is energized. Coil C when energized acts only to pull switch S1 open after switch S2 has been thermally opened, and in such action moves the interlocking connection into position to hold switch S2 in its open position.

This connection comprises an insulated arm A4 carried by the armature switch S1 which normally allows full opening movement of switch S2, but which moves into engagement with switch S2 when switch S1 is opened to hold switch S2 open, this holding action being due to the magnetic attraction of the coil. A condenser C' omitted in Figs. 3, 4 and 5, but shown in the lamp circuits, is included in the starter to reduce the arcing at the contacts in accordance with customary practice. A stop A5 is provided to limit the travel of thermal switch S3 when heated.

In the drawings I have shown five types of circuits for fluorescent lamps as examples of types in which the starter A, in the forms disclosed, or by simple changes in the wiring or arrangements of parts, may be used to secure prompt and reliable starting actions of a lamp in good order and which may be used to secure a cut-out or lock-out action to avoid undue repetitive starting attempts if the lamp is defective or has reached the end of its useful life period.

Referring now to Fig. 1 of the drawing, showing a circuit for operation of lamps on D. C., 5 designates the lamp having a filamentary electrode 6 adapted to be pre-heated and a cooperating electrode 7 which, as shown, is open-circuited, and 8^a and 9^b designate the input and output line leads extending from the line terminals to the starter contact terminals 1 and 3 through which current is supplied to the lamp. The circuit includes a reactor R arranged in conductor 8^a ahead of the starter terminal 1 and a branch 14^b connecting it therewith, a branch conductor 8^c leading from the conductor 8^a, at a point between the reactor and terminal 1, to one terminal of the electrode 7, a ballast lamp BL in the conductor 8^c, and a preheating conductor 10^b, containing a current limiting resistance R1, leading from the starter contact terminal 2

to the input end of the electrode 6, from the output end of which the negative return conductor 11^b leads to the starter contact terminal 4. Conductors 8^c, 10^b, 11^b and 9^b form with their component parts and cooperating parts of the starter per se a lamp preheating or starting circuit while conductors 8^c, 8^a, 11^b and 9^b form with the electrodes and cooperating parts of the starter per se an operating circuit for the lamp.

The starter switch circuit arrangement as shown in Fig. 1 comprises input conductors 12^b, 13^b connected with the terminals 1 and 2, output conductors 15^b, 15^b connected with the terminals 4 and 3, a relay switch S1 normally connecting the output ends of conductors 12^b, 13^b, a relay coil C connected in series with the terminals 3 and 4 between the conductors 15^b, 15^b, a thermostatic time delay switch S2 normally connecting the conductors 15^b, 15^b and extending across the coil C, a thermostatic cut-out switch S3 connecting the input end of conductor 12^b with the terminal 1, a heater H1 for the switch S2 arranged in conductor 12^b, a heater H2 for the switch S3 connected between and in series with said conductor 12^b and switch S3 when the latter is closed, and a supplemental or auxiliary heater H3 for the switch S3 connected in conductor 12^b between the terminal 1 and heater H1 across the switch S3, a mechanical interlocking connection MIC of the type described, and an arc suppressing condenser C' connected between terminals 1 and 2, by which connection it serves to suppress arcs upon the opening of either magnetic switch S1 or thermal switch S3.

With the parts normally arranged as shown in Fig. 1 the switches S1, S2, S3 and heaters H1, H2 are connected in series with each other and with the electrode 6 and line conductors to form a closed preheating circuit to preheat the electrode when the line circuit is closed for a lamp starting operation, during which time a bypass is formed by the conductors 15^b, 15^b and closed switch S2 which shunts the coil C out of the path of flow of the preheating current so that it remains de-energized until the switch S2 opens and breaks the shunt across the coil.

Heaters H1, H2 may be open coil heaters of suitable resistance, heater H2 being of such resistance and so located that the current flowing through it will not heat it enough to cause thermal switch S3 to open its contacts during a normal starting action, but repetitions of starting actions, such as occur with a defective lamp or one which has reached the end of its useful life, will heat heater H2 sufficiently so that it will cause switch S3 to open its contacts. Heater H3, which may be a carbon resistor, is of high resistance as compared with heaters H1, H2, but it is so arranged that once the contacts of thermal switch S3 have opened, it (heater H3) will have substantially line voltage applied across it to keep the contacts of thermal switch S3 open.

The circuit construction described adapts it to be used with a starter having only four contact terminals and applicable to a lamp starter socket of conventional type.

In this circuit when starting, preheating current flows through the reactor to terminal 1 of the starter, through switch S3, heaters H2 and H1, through switch S1 to terminal 2 of the starter, through resistance R1, through the negative filament 6 of the lamp to terminal 4 of the starter, through thermal switch S2 to terminal 3 of the starter, and thence back to the negative side of the line. Heater H2 as described above, is of relatively low resistance, but is so proportioned and so located with respect to heater H1 that it does not act as quickly on thermal switch S3 as heater H1 does on thermal switch S2. Therefore, during a normal starting action it plays no part. Heater H3 is effectively short-circuited during a normal starting action.

The flow of preheating current continues until heater H1 has heated sufficiently to cause thermal switch S2 to open its contacts. When they open, they cut coil C into

the preheating circuit. This causes the coil to open switch S1 by magnetic action and break the preheating circuit through the lamp rapidly. This causes the lamp, if in good condition, to fire, and after it has fired, operating current flows from the positive side of the line through the reactor, through the ballast lamp, to the positive filament 7 of the lamp, through the gas in the lamp itself to the negative filament 6, thence to terminal 4 of the starter, through coil C to terminal 3 of the starter, and thence to the negative terminal of the line. Coil C being energized, holds switch S1 open by magnetic action, and by means of the mechanical interlock MIC also holds the contacts of thermal switch S2 open after the heater H1 cools off.

If while the lamp is operating normally, the line circuit is opened, coil C immediately allows switches S1 and S2 to reclose, so as to be ready for another starting action upon the line circuit being reclosed.

A normal starting action does not heat heater H2 sufficiently for it to have effect enough on thermal switch S3 to cause it to open its contacts, and once the lamp has fired, all heat is removed from heater H2.

Should the lamp fail to start, however, it will make several attempts to do so and each time the heat in heater H2 is increased, until it heats up sufficiently to cause thermal switch S3 to open its contacts. The opening of switch contacts S3 cuts current off the lamp and also connects heater H3 substantially across the line. H3 is of high resistance but of sufficient capacity to keep thermal switch S3 open. Switches S1 and S2 reclose under this condition. The only current flowing through the circuit is the small amount through heater H3.

In a circuit embodying the multiple action lockout feature above described, an appreciable time delay (several minutes) will be required when the line circuit is opened for heater H3 to cool sufficiently to allow thermal switch S3 to reclose its contacts, so that the starter is ready to restart a lamp. This time delay can be avoided, however, by replacing the defective fluorescent lamp and the starter at the same time. The starter can then be used in some other circuit later, as it will not have been damaged in any way.

Figure 2 shows an operating circuit suitable for A. C. or D. C. fluorescent lamps and which also has the multiple action lock-out feature, and in which the arrangement of the parts of the starter are the same as in Fig. 1, but the circuit varies from that shown in Fig. 1 in that one line conductor 8^b containing the reactor R and the ballast lamp BL is connected by a conductor 8^c with one terminal of electrode 7, the other terminal of which is connected by a conductor 10^d with starter terminal 2, while a conductor 10^c containing a current limiting resistance R1, connects the starter terminal 1 with the input terminal of electrode 6, thus connecting both electrodes for a preheating action in series with the line through the starter. The ballast lamp used in this circuit can be omitted if the other requirements of the circuit permit it.

In this circuit when starting, preheating current flows from one side 8^b of the line through the reactor, through the ballast lamp, if used, through filament 7 of the fluorescent lamp to terminal 2 of the starter, through switch S1, heater H1, heater H2, thermal switch S3, to terminal 1 of the starter, through resistance R1, through the other filament 6 of the fluorescent lamp to terminal 4 of the starter, through thermal switch S2 to terminal 3 of the starter, and thence to the other side of the line. The action both in normal starting and in cut-out actions is substantially the same as described with respect to Fig. 1, except that both filaments of the lamp are used in starting, and will be apparent, therefore, not be described in detail.

Fig. 6 shows a circuit arrangement and starter, similar to that of Fig. 1, for use on D. C. in which the starter in cut-out position effectively opens the connection between one line terminal and the lamp in order to eliminate

fate discharge through the lamp of current at low current values and prevent what is known as "ghost lighting" due to this cause, while Fig. 7 shows a circuit arrangement and starter similar to that of Fig. 2 in which the starter in cut-out position acts in the same manner to prevent "ghost lighting."

In each of these circuits the starter varies from those shown in Figs. 1 and 2 in that the switches S1 and S2 are connected in a different manner in the starter circuits, the principal difference being in the arrangement of the wires 12^b, 12^b' and 15^b' which in Figs. 6 and 7 connect heaters H1, H2 in series with switch S1 between starter terminals 1 and 2 and connect switch S3 and heater H3 in series in the circuit connection between switch S2 and the line instead of that between switch S1 and the line, as shown in Figs. 1 and 2, so that switch S3 is connected directly with the starter terminal 3. By this arrangement connection to one side of the line is positively broken when switch S3 opens, as heater H3, which still connects the lamp to the line after switch S3 opens, will not pass enough current to cause "ghost lighting."

Fig. 8 shows the starter as designed for use with the long 48", T-12 lamps used largely in industrial lighting applications. The use of a cut-out feature operative in its cut-out position to disconnect one line terminal from the lamp to prevent "ghost lighting" due to lamp discharge at low current values, as above described, is more necessary with long lamps of the 48", T-12 type than with shorter lamps operated on A. C. or D. C., as such long lamps are especially subject to the objection mentioned on account of the high voltage impressed on them.

The circuit design shown in Fig. 8 is one in which a reactor-transformer R-T is connected by its primary across the line and by its secondary with conductor 10ⁱ leading from one side of the line to the input terminal of electrode 6, whose output terminal is connected by conductor 11^b with the starter terminal 2 and connected in series through the starter and conductors 10ⁱ, 10^j with starter terminal 3 and conductor 9^b leading to the other side of the line, the elements of the starter shown in Fig. 8 being the same in construction and arrangement as that shown in Figs. 6 and 7.

The operation of the circuit and starter arrangements shown in Figs. 6, 7 and 8 is substantially the same as that described with respect to Figs. 1 and 2, with the exception of the above-described line cut-out action of switch S3, so that a detailed description thereof is unnecessary.

Switch S3 in the circuits of Figs. 6, 7 and 8 has a desirable function, in addition to that of effecting the lock-out action. While lamps of the 48", T-12 type allow operation of a lock-out starter into lock-out position after they have reached the end of their useful life, they may still continue to pass current at a low value unless one filament is disconnected from the line, which is not effected at all or with certainty by many starters of this type in general use. This low current passage usually causes flickering or "ghost lighting" which is annoying and objectionable. My improved type of starter effectually overcomes this objection in an obvious manner.

A starter embodying the present invention has the following two major advantages over prior starters, to wit, (1) the preheating or starting circuit is broken rapidly by the opening of switch S1 by magnetic means. This causes the reactor to give a higher inductive kick than that obtained from the slower opening of straight thermal or glow switch starters when used in the same circuits. The higher inductive kick not only makes the firing more certain, but will also effect the firing of lamps that might be discarded under the impression that they had reached the end of their useful life period. (2) In all normal operation of the lamps, due to the switch S1 being held open magnetically by the coil C by the flow of current

through the lamp, the switch will open immediately if the line circuit is opened, and in so doing allow switch S2 to also reclose, so that the starter is ready for another starter action as soon as the line circuit is reclosed. This is not so in the case of a straight thermal starter, where it is necessary for the heater to cool off before its contacts can reclose.

10 (3) If the lamp fails to start after a number of actuations of the starter the cut-out switch, initially actuated by the preheating current, and held in the cut-out or open position by a high resistance heater connected substantially across the line by the opening of the cut-out switch, effectively prevents further actuations of the starter and, if desired, also disconnects one terminal of the lamp from the source of line voltage.

15 From the foregoing description, taken in connection with the drawings, the construction and operation of the starter and circuits disclosed will be readily understood without a further and extended description, and it will be seen that the invention provides a starter of simple and economical type which facilitates and renders easier the starting of hard starting lamps, and one which provides means for securing a quick restarting when desired and means for locking out the starter from continuous or undesired repeating actions to prevent damage to the starter or other components of the circuit in the case of a defective lamp, or a lamp which has reached the end of its useful life. While the constructions shown for these purposes are preferred, it is to be understood that they are merely exemplificative, and that changes in the form, construction and arrangement of parts, falling within the scope of the appended claims, may be made without departing from the spirit of the invention.

Having thus described my invention, I claim:

- 35 1. In a system for starting and operating an electric discharge device comprising a gaseous electric discharge device having at least one electrode constructed to receive preheating current, a normally closed electromagnetic switch and a normally closed time delay thermostatic switch having an operating heater, means including an inductance device and the winding of said electromagnetic switch for connecting said electrodes with a source of current supply, a preheating circuit capable of producing firing temperature electrode heating, said circuit extending from one side of said supply source to the opposite side thereof and including in series connection said inductance device, said electromagnetic switch, the heater for said time delay switch, said winding and at least one of said electrodes, said time delay switch being 40 connected across said winding so that the opening of said switch introduces said winding into the preheating circuit and causes rapid opening of the electromagnetic switch to cause the discharge device to fire by an inductive voltage kick, and mechanical means operatively interconnecting said electromagnetic switch and said time delay thermostatic switch to hold said latter switch open after the heater therefor cools, the operating current of said device continuing to energize said winding and hold both of said switches open during the operation of the device, and, should the device not fire, said electromagnetic switch continuing to open and close thereby repeatedly attempting to cause the device to fire, the combination of mechanism operative after several such actuations of said switch to prevent further actuation thereof comprising a cut-out thermostatic switch having main and auxiliary heaters, said switch and main heater being connected in series in the preheating circuit, and said auxiliary heater being connected in a circuit which is connected across said cut-out switch so that after the several actuations of said electromagnetic switch the cut-out switch is opened by the heat from said main heater, said switch being thereafter maintained open by heat from said auxiliary heater, said auxiliary heater having a resistance value which limits the current through the preheating circuit
- 45 50 55 60 65 70 75 80 85 90 95

to a magnitude insufficient to open said electromagnetic switch.

2. A system for starting and operating a gaseous electric discharge device as claimed in claim 1 in which both electrodes of the discharge device are included in the preheating circuit.

3. A system for starting and operating a gaseous electric discharge device as claimed in claim 1 in which the cut-out switch is connected in that portion of the preheating circuit which is between one of the electrodes and one side of the supply source so that the opening of said switch disconnects said electrode from the supply source.

4. In a system for starting and operating an electric discharge device comprising a gaseous electric discharge device having two electrodes, at least one of which is constructed to receive preheating current, a normally closed electromagnetic switch and a normally closed time delay thermostatic switch having an operating heater, an inductance device, one of said electrodes being connected to one side of a source of current supply through the winding of said electromagnetic switch and the other electrode being connected to the opposite side of said source through said inductance device, a preheating circuit capable of producing firing temperature electrode heating, said circuit extending from one side of said supply source and including in series connection said inductance device, said electromagnetic switch, the heater for said time delay switch and at least one of said electrodes, said circuit continuing through said winding to the opposite side of said current supply, said time delay switch being connected across said winding so that the opening of said switch introduces said winding into the preheating circuit and causes rapid opening of the electromagnetic switch to cause the discharge device to fire by an inductive voltage kick, and mechanical means operatively interconnecting said electromagnetic switch and said time delay thermostatic switch to hold said latter switch open

after the heater therefor cools, the operating current of said device continuing to energize said winding and hold both of said switches open during the operation of the device, and, should the device not fire, said electromagnetic switch continuing to open and close thereby repeatedly attempting to cause the device to fire, the combination of mechanism operative after several such actuations of said switch to prevent further actuation thereof comprising a cut-out thermostatic switch having main and auxiliary heaters, said switch and main heater being connected in series in the preheating circuit, and said auxiliary heater being connected in a circuit which is connected across said cut-out switch so that after the several actuations of said electromagnetic switch the cut-out switch is opened by the heat from said main heater, said switch being thereafter maintained open by heat from said auxiliary heater, said auxiliary heater having a resistance value which limits the current through the preheating circuit to a magnitude insufficient to open said electromagnetic switch.

5. A system for starting and operating a gaseous electric discharge device as claimed in claim 4 in which both electrodes of the discharge device are included in the preheating circuit.

6. A system for starting and operating a gaseous electric discharge device as claimed in claim 4 in which the cut-out switch is connected in that portion of the preheating circuit which is between one of the electrodes and one side of the supply source so that the opening of said switch disconnects said electrode from the supply source.
